DEVICE FOR PRODUCING MULTIPLE FLASH SIGNALS

Hugo Abramson, Lidingo, Sweden, assignor to
American Gas Accumulator Company, Elizabeth, N. J., a corporation of New Jersey

Application March 24, 1937, Serial No. 132,752
In Sweden April 3, 1936

9 Claims. (Cl. 67—111)

My invention relates to flashing gas burners and particularly to flashing burners which are operated by variation in the pressure of the gaseous fuel. Such devices include a valve for regulating flow of gas to the burner, which valve is operated by means of a member such as a diaphragm movable in response to variations in gaseous pressure. The gaseous fuel is supplied at a substantial constant pressure to the diaphragm 5 chamber where it builds up a pressure sufficient to open the valve. The areas of the passages for flow of gas to and from the diaphragm chamber are so proportioned that, when the valve is open gas flows to the burner faster than it is admitted 10 to the chamber. This results in a reduction in pressure and the diaphragm closes the valve. Consequently, gaseous fuel is supplied intermittently to the burner which hence gives a flashing light.

20 For certain purposes, such as signalling at sea, it is desirable that multiple flash signals be obtained. For instance, it may be desired to have the light give three equally spaced flashes followed by a longer period of darkness and then by 25 three more equally spaced flashes. This may be accomplished by connecting two diaphragm controlled valves in series, the first in the line of flow having a lower frequency than the second. For the example given, the first valve should remain 30 open long enough to permit the passage of sufficient gas to cause the second valve to open and close three times. However, as a practical matter, it is impossible to so nicely set the two valves that the second will pass, for instance, in three 35 openings the exact amount of gas which is passed by the first valve in one opening. If the first valve permits a slightly excessive amount of gas to pass, this will accumulate in the connecting conduit and in the diaphragm chamber of the 40 second valve until there is an excess amount present which is sufficient to cause an extra opening of the second valve. Thus, a device adjusted to operate with three flashes separated by a longer period of darkness, every so often will give four 45 flashes instead of three. Likewise, if the first valve permits an insufficient quantity of gas to pass, every so often two flashes instead of three will be obtained.

One of the objects of the present invention is to 50 provide means for remedying the above defect. In accordance with my invention I provide pressure responsive means for automatically regulating either the amount of gas passed by the first valve or by the second valve so that these amounts bear the proper relation to each other.

Further objects and advantages of my invention will be apparent from the following description considered in connection with the accompanying drawings which form a part of this specification and of which:

Fig. 1 is a diagram showing the flow of gas to the burner plotted against time;

Fig. 2 is a more or less diagrammatic cross-sectional view of one embodiment of my invention;

Fig. 3 is a similar view of another embodiment; 10 and

Fig. 4 is a similar view of a third embodiment.

Referring more particularly to Fig. 2, reference character 1 designates a container in which is disposed a flexible diaphragm 2 defining with the 15 upper part of the container a diaphragm chamber 3. A conduit 4 supplies gaseous fuel under pressure to chamber 3 through a throttling device 5. A conduit 6 leads from chamber 3 and flow 20 through this conduit is controlled by means of a valve member 7 which may be pivoted between knife edges 8. The internal cross-sectional area of conduit 6 is greater than that of throttle 5, whereby gas will flow out of chamber 3, when valve 7 is open, faster than it flows in. 25

Secured to valve member 7 is an arm 9 which engages within an aperture formed in a projection 10 on the diaphragm. The aperture is somewhat larger than arm 9 so as to constitute a lost motion connection. Thus the diaphragm may move a 30 certain amount without moving the valve member. The valve member 7 and the lower end 11 of conduit 6, which forms the valve seat, may be of magnetized material, whereby the valve member remains against seat 11 until acted upon by 35 the diaphragm. A spring 12 is disposed between the diaphragm and the bottom of container 1 and acts to move the diaphragm upwardly. The space 13 between the diaphragm and the bottom of the container is in communication with the atmosphere. The apparatus so far described may be 40 termed a primary flasher.

Conduit 6 leads to a secondary flasher which is in all respects similar to the one just described and like parts are designated by similar reference 45 characters to which have been added a prime. However, the strength of spring 12' in the secondary flasher is less than that of spring 12 in the primary flasher in order that the valve 7' may be operated on smaller variations of pressure than is required to operate the valve member 7. This gives the secondary flasher a higher frequency than that of the primary flasher.

Conduit 6' leading from the secondary flasher leads to a gas burner 14. 55

A conduit 15 communicates with diaphragm chamber 3 of the primary flasher and leads to a container 16 which is divided into two chambers by means of a flexible diaphragm 17. Conduit 15 5 communicates with chamber 18 formed beneath the diaphragm. Chamber 19, formed on the other side of the diaphragm, communicates with conduit 6 through a conduit 20. A spring 21 is disposed within chamber 19 and a set-screw 22 is 10 provided for adjusting the tension of the spring. Container 16 and associated elements constitute an automatic pressure responsive regulator, as will be described hereinafter.

The above described device operates as follows:

Gas under pressure is constantly admitted to diaphragm chamber 3 of the primary flasher through conduit 4 and throttling device 5. Valve member 7 at this time is assumed to be in contact 20 with seat 11 and consequently pressure is built up within chamber 3. This pressure moves the diaphragm 2 downwardly against the force of spring 12 and, when sufficient movement of the diaphragm has taken place to take up the play 25 between members 9 and 10, valve member 7 is moved to an open position. Gas then flows through conduit 6 and throttling device 5' to within diaphragm chamber 3' of the secondary flasher where it builds up pressure until diaphragm 2' opens valve member 7'. Gas then flows 30 to the burner 14 where it is ignited by a constantly burning pilot light, not shown. The internal cross-sectional area of conduit 6' is larger than that of throttle 5' and hence gas flows 35 out of diaphragm chamber 3' faster than it is admitted thereto, causing the pressure therein to decrease and diaphragm 2' closes valve member 7', thus shutting off flow of gas to the burner and the light is extinguished. The pressure 40 in chamber 3' now begins to build up again and the cycle of operations is repeated. The primary flasher is adjusted so that valve member 7 remains open and gas is supplied through conduit 6 to the secondary flasher until the valve of the 45 secondary flasher is opened and closed a certain number of times, for instance three. At this time, the pressure in chamber 3 has dropped sufficiently so that valve member 7 is closed and the flow of gas to the secondary flasher is stopped. 50 There then results a period of darkness lasting until the pressure in chamber 3 is again built up to a value sufficient to open valve member 7.

The above cycle of operation is graphically shown in Fig. 1. The secondary flasher is adjusted so that the valve member 7' remains open during the time T_1 and remains closed during the time T_2 . The primary flasher is adjusted so that the valve 7 remains open during the time T_3 and remains closed during the time T_4 . There hence 55 results a flashing period T_3 during which time three flashes T_1 are produced. This is then followed by a long dark period T_4 . The valve 7 thus performs a complete cycle in the times T_3 plus T_4 , and this may be termed a function period of 60 the valve 7.

However, it is practically impossible to so adjust the two flashers that the amount of gas passed by the primary flasher in the time T_3 is 65 exactly equal to the amount passed by the secondary flasher in the same length of time. If the primary flasher permits an excessive amount of gas to pass, the pressure in the chamber 3' will have started to increase for the fourth time at the instant the valve 7 of the primary flasher 70 closes. Hence, when the valve 7 opens in the 75

next cycle there will be a residue of gas present in the conduit 6 and the chamber 3' which will cause the diaphragm 2' to open the valve 7' somewhat sooner than would otherwise be the case. This residue will accumulate during successive cycles and consequently will eventually amount to enough to actuate the diaphragm 2' 10 in an extra time, thus every so often resulting in four consecutive flashes of the burner 14 instead of the desired three.

This extra gas present in the conduit 6 and chamber 3' is utilized to regulate the amount of gas passed by the primary flasher. Assume first that no excess gas has been passed by the primary flasher. Under this condition, a pressure 15 will exist in conduit 6 and chamber 3' during dark period T_4 which is determined by the pressure at which diaphragm 2' closes valve 7'. This pressure is exerted through conduit 20 on the upper side of diaphragm 17. As the pressure 20 builds up in chamber 3 of the primary flasher while valve 7 is closed, this pressure is communicated through conduit 15 to chamber 18 and displaces diaphragm 17 upwardly against the force of spring 21 and the pressure in chamber 25 30 35 40 45 50 55 60 65 70 75 80 85 90 95 100 105 110 115 120 125 130 135 140 145 150 155 160 165 170 175 180 185 190 195 200 205 210 215 220 225 230 ing through the primary flasher and through the secondary flasher is maintained constant within close limits.

As will be seen, the pressure of the residue gas in conduit 6 is practically equal to the maximum pressure required to open the valve of the primary flasher (and hence the maximum pressure existing in chamber 18) minus the pressure of the spring 21. Consequently by regulating the tension of this spring by means of the setscrew 22 the desired residual pressure in conduit 6 and chamber 3' may be obtained.

In Fig. 1 the end of the final period T_1 is shown as coinciding exactly with the end of period T_3 . As previously explained the valve 7' may close for the third time while valve 7 is still open, thus terminating the final period T_1 earlier than period T_3 is terminated. In such an event, the automatic regulator operates to reduce the amount of gas passed by valve 7 during its next function period, as above described. Consequently, over a plurality of function periods, both valves pass the same total quantity of gas. It may also happen that the valve 7 closes before valve 7' has closed for the final time, whereupon the final period T_1 is not terminated until after the termination of period T_3 , but extends over slightly into the period T_4 . However, under this condition, there is no excessive residual pressure in chamber 3' and conduit 6 and the effect is not cumulative, as the valve 7' in three openings has passed the same amount of gas as has the valve 7 in one opening. Thus, under either condition, both valves pass the same total quantity of gas during a plurality of function periods of the valve 7.

In the device shown in Fig. 2, the pressure of the gas required to operate the diaphragm 2 to open valve 7 remains constant. However, the amount of gas passing through the primary flasher may be varied if the pressure at which valve 7 opens is varied. If the valve opens at a lower pressure, the flow of gas through the valve controlled opening will be less, inasmuch as flow of gas through an orifice or conduit varies with the pressure drop therethrough.

In the apparatus shown in Fig. 3 control is effected in this manner. In this apparatus the primary flasher includes a container 25 divided into three chambers by means of two diaphragms 26 and 27. The lower part of container 25 is of greater diameter than the upper part and hence the area of diaphragm 27 is greater than that of diaphragm 26. The diaphragms are connected together by means of a rigid member 28, which also engages with play the arm 9 on valve member 7. A spring 29 is disposed between the bottom of container 25 and lower diaphragm 27.

Conduit 6 communicates with a secondary flasher which, as shown, may be identical with that shown in Fig. 2 and the same reference characters have been employed.

A conduit 30 connects conduit 6 with the space 31 between diaphragms 26 and 27.

It will be seen that the resultant force acting on valve member 7 is equal to the pressure of the gas acting on the upper side of diaphragm 26, minus the pressure of the gas acting on the lower side of this diaphragm, plus the pressure of the gas acting downwardly on diaphragm 27, minus the pressure of the spring 29 acting upwardly. Inasmuch as diaphragm 27 has a larger surface than diaphragm 26, an increase in pressure of the gas within chamber 31 will increase the resultant downwardly acting gas pressure ex-

erted against spring 29. Consequently if the residual pressure in conduit 6, and chamber 3', and hence in chamber 31, is higher, less pressure will be required in chamber 3 to open valve 7 than would be the case if the residual pressure were lower. If the valve 7 opens at lower pressure the gas will pass through conduit 6 at a slower rate than it would if the pressure were higher. Consequently less gas will be passed by the primary flasher.

On the other hand, if in the previous cycle the primary flasher has not passed enough gas this will be reflected in a lower residual pressure in conduit 6 and chamber 31 and a higher pressure in chamber 3 will be required to open the valve. This higher pressure will result in gas passing through conduit 6 at a more rapid rate. Consequently, the amount of gas passed by the primary flasher is controlled by the residual pressure and the same ultimate result is obtained with this apparatus as with the apparatus shown in Fig. 2.

Instead of regulating the amount of gas passed by the primary flasher in order to maintain equal the amounts passed by the two flashers, the same ultimate result may be obtained by regulating the amount passed by the secondary flasher. An apparatus operating in this manner is shown in Fig. 4.

In Fig. 4 the primary flasher may be identical with that shown in Fig. 2 and corresponding parts are designated by the same reference characters. The secondary flasher, however, consists of a container 35 divided by a diaphragm 36 into chambers 37 and 38, both chambers being closed to the atmosphere. Conduit 6 communicates through throttling device 5' with chamber 37. A valve member 7' is controlled by diaphragm 36. A conduit 39 connects conduit 6 with chamber 38, the conduit being provided with a throttling device 40. A spring 41 is disposed in chamber 38 and bears upwardly against the diaphragm 36.

In the device above described, if the residual pressure in conduit 6 and chamber 37 is high at the time valve 7' closes, this pressure during the dark period T_4 builds up in chamber 38 through throttling device 40. Consequently, when valve 7' in the primary flasher again opens and admits gas to chamber 37, a higher pressure in this chamber is required in order to move the diaphragm 36 sufficiently to open valve 7'. When, however, the valve does open the gas passes into conduit 6' to the burner at a higher rate due to this higher pressure. Consequently, the secondary flasher consumes more gas when the residual pressure is high than when it is low. Thus, if the primary flasher tends to pass too much gas, the secondary flasher is regulated to consume this gas and in this way the ratio between the amounts of gas passing through the two flashers is maintained constant.

While I have shown three more or less specific embodiments of my invention, it is to be understood that this has been done for the purposes of illustration only and is not to be considered as limiting the scope of my invention, which is to be determined by the appended claims viewed in the light of the prior art.

What I claim is:

1. In a device for producing multiple flash signals by an illuminating gas burner, a first valve, means responsive to variations in pressure of the illuminating gas for intermittently opening and closing said valve at regular intervals, a second valve connected in series with said first valve, means responsive to variations in pressure of the

- illuminating gas for intermittently opening and closing said second valve at regular intervals a plurality of times while said first valve is open, and means responsive to variations in pressure of the illuminating gas for automatically maintaining equal the amounts of gas passed by said valves during a plurality of function periods of said first valve.
2. In a device for producing multiple flash signals, a first valve, means responsive to variations in pressure of gas ahead of said valve for opening and closing said valve at regular intervals, a second valve connected in series with said first valve, means responsive to variations in pressure of gas ahead of said second valve for opening and closing said second valve at regular intervals a plurality of times each time said first valve is open, and means responsive to pressure between said valves for maintaining equal the quantities of gas passed by said valves during a plurality of function periods of said first valve.
3. In a device for producing multiple flash signals by an illuminating gas burner, a first valve, means responsive to variations in pressure of the illuminating gas for intermittently opening and closing said valve at regular intervals, a second valve connected in series with said first valve, means responsive to variations in pressure of the illuminating gas for intermittently opening and closing said second valve at regular intervals a plurality of times while said first valve is open, and means responsive to variations in pressure of the illuminating gas for regulating the amount of gas passed by said first valve so as to maintain equal the amounts of gas passed by the two valves during a plurality of function periods of said first valve.
4. In a device for producing multiple flash signals by an illuminating gas burner, a first valve, means responsive to variations in pressure of the illuminating gas for intermittently opening and closing said valve at regular intervals, a second valve connected in series with said first valve, means responsive to variations in pressure of the illuminating gas for intermittently opening and closing said second valve at regular intervals a plurality of times while said first valve is open, and means responsive to variations in pressure of illuminating gas for regulating the amount of gas passed by said second valve so as to maintain substantially equal the amounts of gas passed by the two valves during a plurality of function periods of said first valve.
5. In a device for producing multiple flash signals, a first valve, means responsive to variations in pressure of gas ahead of said valve for opening and closing said valve at regular intervals, a second valve connected in series with said first valve, means responsive to variations in pressure of gas ahead of said second valve for opening and closing said second valve at regular intervals a plurality of times each time said first valve is open, and means responsive to pressure between said valves for regulating the quantity of gas passed by said first valve so as to maintain substantially equal the quantities of gas passed by the two valves during a plurality of function periods of said first valve.
6. In a device for producing multiple flash signals, a first valve, means responsive to variations in pressure of gas ahead of said valve for opening and closing said valve at regular intervals, a second valve connected in series with said first valve, means responsive to variations in pressure of gas ahead of said second valve for opening and closing said second valve at regular intervals a plurality of times each time said first valve is open, and means responsive to pressure between said valves for regulating the quantity of gas passed by said second valve so as to maintain substantially equal the quantities of gas passed by the two valves during a plurality of function periods of said first valve.
7. In a device for producing multiple flash signals, a first valve, means responsive to variations in pressure of gas ahead of said valve for opening and closing said valve at regular intervals, a second valve, means responsive to variations in pressure of gas ahead of said second valve for opening and closing said second valve at regular intervals a plurality of times each time said first valve is open, conduit means connecting said valves in series, means defining a closed space, a displaceable diaphragm dividing said space into a first chamber and a second chamber, the first chamber being connected ahead of said first valve and the second chamber being connected to said conduit between said valves, and resilient means for resisting displacement of said diaphragm by gas in said first chamber.
8. In a device for producing multiple flash signals, a container, a first diaphragm and a second diaphragm disposed in said container, said first diaphragm having less area than said second diaphragm and said diaphragms being rigidly connected so as to move in unison, means for supplying gas to the chamber bounded by said first diaphragm, a conduit leading from said chamber, a valve controlled by movement of said diaphragm for regulating flow of gas from said chamber through said conduit, a second valve fed by gas from said conduit, means responsive to variations of pressure of gas ahead of said second valve for opening and closing said second valve at regular intervals during the time said first valve is open, means establishing communication between said conduit and the chamber formed between said first and second diaphragms, and resilient means urging said diaphragms in a direction to close said first valve.
9. In a device for producing multiple flash signals, a first valve, means responsive to variations in pressure of gas ahead of said valve for opening and closing said valve at regular intervals, means defining a closed space, a diaphragm dividing said space into a first chamber and a second chamber, a conduit leading from said first valve to said first chamber, a second valve controlled by movement of said diaphragm for regulating flow of gas from said second chamber, and means including a throttling device connecting said conduit with said second chamber.

HUGO ABRAMSON.
